Primary Examiner — Jennifer L Rempfer*Assistant Examiner* — Varun Salil Kamat(74) *Attorney, Agent, or Firm* — Nicholas Makridakis(57) **CLAIM**

The ornamental design for a table, as shown and described.

DESCRIPTION

FIG. 1 is a perspective view of a table showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the table of FIG. 2 in an alternate configuration of use;

FIG. 10 is an enlarged view of the encircled portion '10' in FIG. 1; and,

FIG. 11 is an enlarged view of the encircled portion '11' in FIG. 1.

The equal-length broken lines depict portions of the table that form no part of the claimed design.

The dash-dot lines in FIGS. 1, 10 and 11 illustrate the boundaries of the enlarged view indicators and form no part of the claimed design.
